Henry W. Williams

UNITED STATES PATENT OFFICE.

THOMAS PRATT WEST, OF LYNNFIELD, ASSIGNOR OF ONE-HALF TO ERSKINE F. BICKFORD, OF MALDEN, MASSACHUSETTS.

CLASP FOR SHOES OR OTHER ARTICLES.

SPECIFICATION forming part of Letters Patent No. 320,104, dated June 16, 1885.

Application filed April 13, 1885. (No model.)

To all whom it may concern:

Be it known that I, THOMAS P. WEST, of Lynnfield, in the county of Essex and State of Massachusetts, have invented a new and useful Improvement in Clasps, of which the following is a specification.

This is an improved clasp or buckle-clasp intended, primarily, for use upon shoes; and it is illustrated in the accompanying drawings, 10 in which--

Figure 1 is a perspective view of the clasp with straps or webbing attached. Fig. 2 is a longitudinal section of the same. Fig. 3 is a perspective view of that part of the clasp which 15 embodies my invention with the finger or snap raised. Fig. 4 is a longitudinal section of the same.

Similar letters of reference indicate like parts.

20 A represents a curved plate slotted at *a*, and having a strap or webbing, *A'*, attached to it, said plate being constructed as usual. B and C are two parts constituting a spring-frame of substantially the shapes shown, and coincidently slotted at *b* and *c* to receive the strap or webbing D. The part C of the spring-frame extends back under the part B thereof, as shown, and is provided with a tongue, *C'*, which is bent to extend up through an opening, *B'*, in the frame, and is folded so as to 25 form a hinge or pivot for the finger. E is the finger or snap, whose shaft *E'* lies in the fold in the tongue *C'*. The free end of this finger is constructed substantially as usual; but its

rear or inner end is provided with two projections, *e e*, of essentially the shape shown. As the finger E is swung from the open position shown in Figs. 3 and 4 to the closed position shown in Figs. 1 and 2, or vice versa, the projections *e e* bear and press upon the 35 surface of the frame B, and draw or lift the tongue C' up through the opening B', pulling the part C up toward the said frame. It will 40 thus be seen that the finger cannot be opened or closed—*i. e.*, swung over in either direction—without the application of power greater than would occur without intent on the part of the user, and if started slightly will immediately on being released fly back into its 45 former position.

The operation of buckle clasps on shoes is 50 so well known that no further description is necessary.

Having thus fully described my invention, what I claim, and desire to secure by Letters 55 Patent, is—

In a clasp, the combination of the spring-frame consisting of the part B, provided with the opening B', and the part C, provided with the folded tongue C', extending into said opening, and the finger or snap E, hinged to said tongue and provided with the projections *e e*, all arranged and constructed substantially as 60 and for the purpose set forth.

THOMAS PRATT WEST.
